BATHTUB SHOWER BATH APPLIANCE

Ivar V. Thulin, Upper Darby, Pa.

Application February 5, 1946; Serial No. 645,595

3 Claims. (Cl. 4—148)

1

My invention relates to a new and useful bathtub shower bath appliance and more particularly a shower bath fixture for installation completely within a bath tub and directly connected to a water supply fitting, such as a faucet, leading into the bath tub.

Often, shower bath appliances are installed that require a multiplicity of fittings and fixtures and considerable plumbing work and are, therefore, expensive as well as rather unsightly. In addition they are usually, if not always, arranged so that the major portions are outside of the bath tubs and above the heads of persons using the same. These are disadvantages where a person in medium financial circumstances is concerned and where it is undesirable to wet the hair during the taking of a shower bath.

It is, therefore, a general object of this invention to provide a simple, durable and relatively inexpensive appliance that can be installed on a faucet within a bath tub thus eliminating all outside fittings and fixtures and locating the shower completely within the bath tub and below the head height of a person using the same.

Another object of the invention is to provide a shower bath appliance which is adjustable to direct a spray of water vertically downwardly and at various angles, both forwardly and rearwardly of the vertical according to the angular position of the swinging tubular arm.

Another object of this invention is to provide means for detachably connecting the shower bath appliance to a faucet whereby said appliance becomes, in effect, a part of the faucet.

A further object of the present invention is to so arrange the apertures in the spray nozzle or rose that by rotating said rose a one-quarter turn in either direction, the water may be directed as a wide or narrow spray horizontally, according to the desires of the user.

With the above and other objects in view, this invention consists of the details of construction and combination of elements hereinafter set forth and then designated by the claims.

In order that those skilled in the art to which this invention appertains may understand how to make and use the same, I will describe its construction in detail referring by numerals to the accompanying drawing, in which—

Fig. 1 is a cross sectional view of a bath tub showing the shower bath appliance connected to the faucet by a clamp.

Fig. 2 is a longitudinal sectional view of the bath tub and showing the shower bath appliance from a position at right angles to Fig. 1, and illustrating in dotted lines two others of a num-

2

ber of locations to which the swinging tube may be adjusted.

Fig. 3 is an enlarged front view of the shower bath appliance.

Fig. 4 is side view thereof.

Fig. 5 is a longitudinal sectional view of the same.

Fig. 6 is a further enlarged face view of the spray nozzle or rose.

Fig. 7 is a still further enlarged fragmentary detail sectional view of the appliance in the region of the pivot joint.

Fig. 8 is a fragmentary sectional elevation of a modified part of the appliance.

Fig. 9 also is a fragmentary sectional elevation of another modification.

Fig. 10 is a sectional elevation of a faucet, adapter and shower bath appliance illustrating another way of mounting said appliance.

Fig. 11 is a fragmentary sectional elevation of the shower bath appliance showing one form of construction.

Figs. 12, 13 and 14 are similar views depicting various modifications.

25 In carrying out the invention as herein embodied 15 represents any type of conventional bath tub provided with the usual bottom drain (not shown), the elevated overflow opening 16 leading to the outlet pipe 17, a faucet 18, either of the single or mixing type, and water supply pipe or pipes, one of which is shown at 19, Fig. 2.

The reference numeral 20 indicates the short tubular arm of the shower bath appliance, the outer or free end of which constitutes a plug 35 21 and said plug portion may be plain, for some purposes, as shown in Figs. 4 and 5, or exteriorly threaded, for other purposes to be later described, as shown in Figs. 8 and 10 to 14, inclusive. At the inner end of said short arm 20 is provided

40 one member 22 of a knuckle joint having a chamber 23 in communication with the bore of the short tubular arm, and said member is open at one side for the reception of the male portion 24 of the similar complementary knuckle joint

45 member 25 also having a chamber 26 which is open at one side for communication with the chamber of the other knuckle joint member 22. This chamber also communicates with the bore of the long tubular arm 27 which is swingingly 50 adjustable.

The adjacent sides of the knuckle joint members 22 and 25 have flat faces surrounding the side openings and especially the male portion 24 of one of said members. Between these flat faces 55 is interposed a fibre or other suitable washer 28 and the two knuckle joint members are pivot-

ally held together by suitable fastening means, such as a bolt 29 projected axially through said members with a nut 30 screws onto the threaded end and a metal washer 31 may be placed beneath the head of the bolt.

If found desirable either or both of the tubular arms 26 and 27 and their knuckle joint members may be made in sections. That is, the short arm 26, Figs. 9, 13 and 14, is made up of at least two sections 26a and 26b joined together, as by a threaded joint 32, and the section 26b is connected with the knuckle joint member 22. Likewise, the long tubular arm 27 may consist of at least two sections 27a and 27b, Fig. 9, joined together, as by a threaded joint 33, and the section 27a is connected with the knuckle joint member 25.

Referring particularly to Figs. 1 to 5, inclusive, and 8, a plate or collar 34 is shown on the short tubular arm 20 just to the rear of, below or at the inner end of the plug 21 and this may be formed as an integral part of the structure, as shown in Fig. 5, or it may be a separate element mounted on the structure as by screw threads in the manner illustrated in Fig. 8. To form a water tight seal, a compressible gasket 35, such as a rubber washer, is placed over the plug 21 and seated on the plate or collar 34, for engagement with the edge of the outlet spout of a faucet. A metal strap clamp 36 has one leg fastened to plate or collar 34, at one side of the plug by fastening means 37, while the other leg has an offset engaged by a screw 38 that is threaded through a portion of the plate or collar 34.

By inserting the plug portion in the spout of the faucet and placing the clamp 36 over a part of said faucet above its spout and then positioning and tightening the screw 38, the appliance will be firmly secured to the faucet completely within the bath tub, and a water tight joint between the faucet and appliance will be formed by the gasket 35.

The outer or free end of the long tubular arm 27 is preferably provided with an exterior thread 39 to receive the interiorly threaded socket 40 of the spray nozzle or rose 41 which includes an end wall 42 having perforations 43 arranged in an oblong pattern, Fig. 6. That is, the area of the end wall 42 which is perforated is wider in one direction than the other at right angles to the first.

In lieu of the clamp, the plug 21 may be exteriorly threaded in every instance, as shown in Figs. 10 to 14, inclusive, for direct threaded connection with the interiorly threaded faucet spout, 55 if the two fit each other, or with an adapter 44, Fig. 10, which has exterior threads to fit the interior ones of the faucet spout and also has interior threads to fit the threads of the plug 21. The adapter may be made in various sizes to fit different sized faucet spouts but will always fit the one size of plug 21.

A plate or collar 45, similar to the one first described but not necessarily as large, is carried by the short tubular arm 20 to the rear of, below or at the inner end of the plug 21, and this plate or collar may be formed integral with said short tubular arm whether the latter is in one piece, as in Fig. 11, or of a number of sections, as in Fig. 13. Likewise said plate or collar may be a separate element and mounted on the short tubular arm whether the latter is in one piece, as shown in Fig. 12, or in a number of sections, as indicated in Fig. 14.

With the appliance installed as shown, all of 75

the elements are completely within the bath tub and the swingingly pivoted long tubular arm can be adjusted to the full line position for permitting water to run directly into the tub for filling the latter or it can be swung to the right of said full line position in Fig. 2 so that the water will quietly run down an end wall of the tub whereby persons in rooms adjacent the bath will not be disturbed by splashing or falling water. If the 5 apparatus is to be used for washing the feet, it may be adjusted to some position at approximately the location of the adjacent dotted-line position in Fig. 2. For showering other portions of the body, such as the legs, while standing in the 10 tub, or up to the head, while seated in the tub, the long tubular arm 27 may be manipulated to other intermediate positions. In order to direct the spray to a large vertical and small horizontal area of a person's body, the spray nozzle, 15 head or rose 41 is turned so that the longer diameter of the perforated portion of the wall 42 is in a substantially vertical position as shown in Fig. 6. It can then be used in the highest elevated position without the likelihood of any water flowing over the sides of the tub. When the 20 spray is to be directed to a small vertical and large horizontal area of the body, said spray nozzle, head or rose 41 is rotated a quarter of a turn relative to the position shown in Fig. 6.

The appliance particularly depicted in Figs. 10 to 14, inclusive, can be used as above described and also can be utilized for washing the interior surface of the tub because by rotating the structure in the faucet spout, water can be directed to either side and by raising and lowering the long tubular arm the water will reach from the top to the bottom of said tub. If a stream of water is preferred so that the flow will be similar to that issuing directly from the faucet, the spray nozzle, 25 head or rose 41 may be removed entirely from the long tubular arm 27.

The device described herein is especially adapted for use as a shower without the likelihood of wetting the person's hair as occurs when an overhead spray is employed, and many other utilitarian purposes will be apparent to a user of the appliance.

Of course I do not wish to be limited to the exact details of construction herein shown and described as these may be varied within the scope of the appended claims without departing from the spirit of my invention.

Having described my invention, what I claim as new and useful is:

1. A bathtub shower bath appliance comprising a tubular arm removably connected to a bathtub faucet and in direct communication with the spout of said faucet and extending downwardly therefrom, a long tubular arm pivotally hinged to the lower end of said short arm and communicating with the latter, and a spray head rotatably and removably mounted on the outer end of said long arm, the long arm being swingable from a depending position contiguous the adjacent end wall of the tub and to one side of a vertical plane parallel with said end wall and bisecting the faucet spout, to an elevated position on the opposite side of said plane entirely within the tub.

2. The shower bath appliance of claim 1 wherein the shower head has a perforated end wall with the perforations arranged in a generally oblong area.

3. In combination with a bathtub and its faucet having a threaded spout, a shower bath ap-

pliance for installation entirely within the tub and comprising a short arm having a threaded end constituting a plug, a knuckle joint member on the other end of said short arm, a long tubular arm having a threaded outer end to receive a shower head, a knuckle member on the opposite end of said long arm for rotatable connection with the first mentioned knuckle member, means to hold said members together, a plate on the short arm at the inner end of the plug, a gasket surrounding the plug and engaging the plate, and an adapter for selective mounting on the plug and insertion in the faucet spout.

IVAR V. THULIN.
